PARKING METER

George H. Partin, Memphis, Tenn.

Application July 12, 1944, Serial No. 544,543

6 Claims. (Cl. 194—1)

1

This invention relates to parking meters and has for its purpose the provision of a parking meter which is automatically set to indicate and measure an interval of time upon the insertion of a coin without any manual manipulation of any levers, keys, or other devices.

An object of the invention is to provide a parking meter which is wholly automatic insofar as the operation by the user is concerned and which may be constructed to operate one or a plurality of indicators to be put into operation by the use of coins of different sizes and denominations.

Another object of the invention is to provide a parking meter which has very few moving parts, is easily constructed and assembled, and has practically no mechanism to get out of order.

A further object of the invention is to provide a parking meter in which the coin itself serves to set the parking meter into operation.

A still further object of the invention is to provide a parking meter in which more than one coin of the same denomination may be used so that the interval of time which the meter is designed to set up and measure may be doubled by the insertion of a second coin of the same denomination.

These and other features of the invention will be seen from the following detailed specification read in connection with the accompanying drawings forming part thereof and in which—

Fig. 1 is a front elevation of the interior of the parking meter of this invention;

Fig. 2 is a side elevation of the interior of the parking meter;

Fig. 3 is a plan view of the interior of the parking meter; and

Fig. 4 is an enlarged side elevation partly in section of the interior of the parking meter.

Referring to the drawings, the parking meter comprises a motor case 11 which contains either spring wound or electrically driven motors (not shown) which are of constant speed and which are stopped in their operation whenever the indicator hands have reached the position which indicates exhaustion of the time interval set up on the meter.

If the meter is constructed for use with a single size of coin only one motor is required in the motor case 11, but if a plurality of coins are provided for, a similar number of motors must be provided as each indicator is separately driven and requires its own motor. Of course, a single motor with separate drivers can also be used. If spring motors are used keys 12 may be employed to wind them at various periods when 55

2

the meters are examined or opened for removal of the coins which are placed therein.

No effort is made in these drawings to show the case for the parking meter, the receptacle 5 for the coins used therein, or the other familiar accessories of this type of instrument.

Driven by each of the motors is a hollow shaft and a ratchet wheel at the outer end thereof. The parking meter shown in the accompanying drawings is constructed for the use of two different sized coins, thereby comprising indicators 15 and 16 separately moved by the individual rotation of ratchet wheels 17 and 18 on hollow shafts 31 and 32, respectively. However as the 10 construction for actuation by each of the different sized coins is substantially identical, the description will be confined largely to the description of the mechanism for operation by one size of coin.

20 In such mechanism, the ratchet wheel 18 as shown in Fig. 1, is serrated with uniform teeth spaced at uniform distances about its periphery. The spacing of these teeth is determined by the scale 14 which may be marked in minutes or 25 other denominations of time, and the interval of time which the meter is desired to provide for upon the insertion of a single coin.

The ratchet wheel 18 is formed along its surface with an annular fulcrum ridge 20 upon which the indicator hand 16 is designed to pivot in the manner hereinafter set forth. The indicator hand 16 not only can pivot upon the fulcrum ridge 20 but is mounted so that it may be freely rotated about the shaft 13 which is stationary. The indicator 30 16 is also so shaped that when it is in its normal position it will bear against one of the teeth on the ratchet wheel 18 and be carried by the movement of the ratchet wheel in a counterclockwise direction.

Attached to the indicator 16 is the indicator 35 spring 22 which draws the indicator 16 in a clockwise direction against the movement of the ratchet wheel 18.

Adjacent the ratchet wheel 18 is the coin chute 40 24 into which protrudes the trigger 28 upon the coin lever 26.

The coin lever 26 is pivoted at the pivot 30 and extends to the shaft 13 upon which it is mounted for free movement when swung upon the pivot 30. As indicated in Fig. 4, the coin lever may be provided with a pointed bearing surface so that where it bears against the indicator 16 there will be little friction to interfere with the free movement of the indicator.

50 The lower portion or trigger 28 of coin lever

26 is formed so that passage of a coin 37 through coin chute 24 moves the trigger laterally in the chute. Such movement of the trigger swings lever 26 on pivot 30 thereby moving upper portion 33 of the lever in a direction opposite to the movement of trigger 28. By bearing against lower portion 34 of indicator 16, the lever 26 will force the indicator against annular ridge 20 of ratchet wheel 18. The indicator is thereby pivoted on the ridge so that upper portion 35 of the indicator is moved in a direction opposite to that of lower portion 34 and is thereby freed from the engaging tooth 36 of ratchet wheel 18.

As ratchet wheels 19 and 20 are individually mounted on hollow shafts 31 and 32, each ratchet wheel is free to move without regard to the movement of the other ratchet wheel. Where the parking meter is constructed so as to be operated by more than two sizes of coins, additional ratchet wheels, each mounted on its individual hollow shaft, may be supported on stationary shaft 13.

Method of operation

With the motor of the parking meter wound, if spring driven, or under power if electrically driven, the motor continually urges the ratchet wheel 18 and the indicator engaging the ratchet tooth counter-clockwise. When the indicator reaches the end of its range of movement, the resistance to its further movement is sufficient to stop the motor.

A coin then dropped into the coin chute 24 will strike the trigger 28 and swing the lever 26 about its pivot 30. The upper end of the lever 26 then bears against the lower end of the indicator 16 and because of the intervening annular ridge 20 the indicator 16 swings along that ridge as a fulcrum and is freed from the tooth of the ratchet wheel 18.

Thereupon the spring 22 pulls the indicator in a clockwise direction free of the ratchet wheel. The coin striking the trigger 28 bears against it only momentarily and by the time the indicator 16 reaches the next ratchet tooth the coin has cleared the trigger and the indicator, also because of the bias of the spring 22, is forced inwardly into engagement with the next ratchet tooth.

The obstruction to further movement of the motor having thus been removed, the motor resumes its rotation at a constant speed and turns the ratchet wheel 18 counter-clockwise to return the indicator 16 to its exhausted position in the interval of time indicated by the scale 14.

If the user of the parking meter desires to double the interval of time to be allotted him by the parking meter he need merely insert a second coin of the same denomination, which will again free the indicator from the ratchet tooth and permit it to be carried by the spring 22 to the next ratchet tooth.

In the parking meter shown in the drawings a second coin chute 23 is shown for use of smaller coins, for example, pennies, and the ratchet wheel teeth are cut, as indicated in the drawings, more closely together so that the insertion of the coin frees the indicator 15 for movement through the shorter distance measured between the teeth on the ratchet wheel 17.

For example, should the meter provide for an interval of sixty minutes upon insertion of a five cent coin, by cutting the teeth on the ratchet wheel 17, one-fifth of the distance of the teeth on the ratchet wheel 18 and using constant speed motors of the same speed, the insertion

of a penny into the coin chute 23 will set the indicator 15 to measure an interval of twelve minutes on the scale 14.

Obviously, if other coins of different denominations are to be accommodated by the meter, these can be provided for by increasing the number of ratchet wheels, indicators, and coin chutes without any substantial alteration in the construction of the parking meter.

Having thus shown and described one embodiment of the invention, it is to be understood that it is capable of many modifications. Changes, therefore, in the construction and arrangement may be made without departing from the spirit and scope of the invention as disclosed in the appended claims, in which it is intended to claim all novelty inherent in the invention as broadly as permissible, in view of the prior art.

I claim:

1. A parking meter comprising a motor, an indicator, a ratchet wheel driven by the motor and having a tooth engageable with the indicator to move the same, and coin-actuated means to lift the indicator from one tooth on the ratchet wheel and to reestablish its driving relation at the next tooth on the ratchet wheel.

2. A parking meter comprising a motor, a ratchet wheel driven by the motor, an indicator engageable with a tooth of the ratchet wheel to be moved thereby, coin-actuated means to free the indicator from the ratchet wheel, and means to shift the indicator from one tooth of the ratchet wheel to the next tooth thereof while freed therefrom and to reengage the indicator with the said next tooth.

3. A parking meter comprising a motor, a ratchet wheel driven by the motor, an indicator engageable with a tooth of the ratchet wheel and driven thereby, means to shift the indicator peripherally with respect to the ratchet wheel when freed therefrom and into engagement with another tooth of the ratchet wheel, a fulcrum on the ratchet wheel upon which the indicator can be swung to free it from the ratchet wheel, and coin-actuated means to swing the indicator free of the ratchet wheel.

4. A parking meter comprising a motor, a ratchet wheel driven by the motor, an indicator engageable by a tooth of the ratchet wheel and driven thereby, an annular ridge on the ratchet wheel on which the indicator can be swung to free it from the ratchet wheel, means to shift the indicator peripherally with respect to the ratchet wheel when freed therefrom and into engagement with another tooth of the ratchet wheel, and a coin-actuated lever to swing the indicator on the annular ridge to free it from the ratchet wheel.

5. A parking meter comprising a motor, a ratchet wheel driven by the motor, an indicator engageable by a tooth of the ratchet wheel and driven thereby, an annular ridge on the ratchet wheel on which the indicator can be swung to free it from the ratchet wheel, means to shift the indicator peripherally with respect to the ratchet wheel when freed therefrom and into engagement with another tooth of the ratchet wheel, a coin chute, a pivoted lever with one end bearing on the indicator to swing it on the annular ridge to free it from the ratchet wheel, and a trigger on the lever and projecting into the coin chute to be moved by a coin for swinging the lever.

6. A parking meter comprising a motor, a

ratchet wheel driven by the motor, an indicator engageable with a tooth of the ratchet wheel to be driven thereby, and coin actuated means to shift the indicator from one tooth of the ratchet wheel to the next tooth thereof.
